(57) CLAIM

I claim the ornamental design for a jewelry cross, as shown and described.

DESCRIPTION

FIG. 1: Front elevation view of my jewelry cross showing my new design

FIG. 2: Back elevation view thereof; and,

FIG. 3: Right elevation view thereof (this view is a mirror image of the left elevation view).

1 Claim, 3 Drawing Sheets

FIG. 1

FIG. 3
